UNITED STATES PATENT OFFICE.

LOUIS C. HECKMAN, OF CLEVELAND, OHIO.

OIL-STOVE.

SPECIFICATION forming part of Letters Patent No. 240,589, dated April 26, 1881.

Application filed December 30, 1880. (No model.)

To all whom it may concern:

Be it known that I, LOUIS C. HECKMAN, of Cleveland, in the county of Cuyahoga and State of Ohio, have invented certain new and useful Improvements in Oil-Stoves; and I do hereby declare the following to be a full, clear, and exact description of the invention, such as will enable others skilled in the art to which it pertains to make and use it, reference being had to the accompanying drawings, which form part of this specification.

My invention relates to oil-stoves, and more particularly to that portion of an oil-stove called the "drum," which consists of a device for supporting cooking utensils, and at the same time carrying the chimneys.

Heretofore it has been customary to construct these drums of a top and bottom of cast metal, chimneys of sheet metal, and a casing about the chimneys of sheet metal, the whole bolted together by a single bolt through the center. There are many objections to drums constructed in this manner, the principal of which is the great inconvenience in cleaning. In cooking food is liable to be spilled or boil over, when it will drop down about the chimneys and upon the lower portion or base of the drum. In the old-fashioned drum the only way to clean it is to loosen the nut attached to the bolt, remove the bolt, and take the drum entirely to pieces.

My invention consists in the combination, with a drum composed of hinged sections adapted to be opened and closed, of chimneys adapted to be removed without disturbing the upper or lower plates of the stove; also, in so constructing the chimneys that they can be readily removed, and in parts and combination of parts, as will more fully hereinafter appear.

In the drawings, Figure 1 is an isometric view of a drum constructed according to my invention. Fig. 2 is a detached view, in detail, of one of the chimneys, showing a modification of the construction shown in Fig. 1. Fig. 3 is an end elevation of one of the chimneys, showing the upper and lower cut-away portions.

In the said drawings, A represents the base or lower plate of a drum adapted for use with an oil-stove, and provided with wick-cones A' permanently attached thereto. These cones

are also provided with stops a, against which the chimneys rest when in position.

B represents the upper plate, which is constructed in the usual well-known manner and adapted for the support of utensils during the process of cooking.

C C are chimneys constructed in the usual well-known manner, with the exception that their back portions, both above and below, are cut away in such a manner that they may be readily slid over the wick-cones A' and the flanges usually attached to the under side of the upper plate, B.

In Fig. 2 is shown a modification of construction, which consists in the attachment of the wick-cones A' permanently to the chimneys C, and also the flanges upon the under side of the upper plate, B. When so constructed the lower plate, A, may be made flat, without any projections whatever, as also may the inner face of the upper plate, B.

D represents the outer casing of the drum, which is hinged at d, and thereby permitted to be thrown back out of the way, as shown in Fig. 1. This construction might be modified by adapting the two portions of which the casing is made to slide in grooves prepared in the upper and lower plates; or one portion of the casing might be permanently attached to the upper and lower plates, and the other portion hinged thereto and adapted to open as a door, the object of the invention being to permit ready access to the interior. The two pieces of which the casing is made may be locked together in any suitable manner.

What I claim is—

1. In a drum adapted for use in coal-oil stoves, a casing made in two or more parts, each part so hinged that it is adapted to move independently of the other, substantially as set forth.

2. In a drum adapted for use in coal-oil stoves, the combination, with a casing made in two parts, each part adapted to move independently of the other, of a chimney so constructed that it may be removed or placed in position without disturbing the upper or lower plates, substantially as set forth.

3. In a drum adapted for use in coal-oil stoves, a wick-cone, A', provided with stop a and chimney C, substantially as set forth.

4. In a drum adapted for use in coal-oil

stoves, the combination, with the lower plate, of a chimney adapted to move laterally over the wick-cone, substantially as set forth.

5. The combination of a wick-cone and a chimney adapted to be moved laterally over said cone, substantially as set forth.

In testimony whereof I have signed my name

to this specification in the presence of two subscribing witnesses.

LOUIS C. HECKMAN.
